UNITED STATES PATENT OFFICE.

EDWARD A. TURNER, OF DAVENPORT, IOWA.

THREAD-HOLDER.

1,261,460.

Specification of Letters Patent.

Patented Apr. 2, 1918.

Application filed December 28, 1915. Serial No. 69,069.

To all whom it may concern:

Be it known that I, EDWARD A. TURNER, a citizen of the United States, residing at Davenport, in the county of Scott and State 5 of Iowa, have invented certain new and useful Improvements in Thread-Holders, of which the following is a specification.

My invention relates to what I shall hereinafter term an improved floss or thread 10 holder and contemplates primarily an improved construction, combination, and arrangement of parts whereby an assortment of silk thread or floss may be conveniently, attractively and effectually displayed.

15 A further object of the invention is to provide in a display case or holder an improved means for holding the various individual threads in a manner permitting the ready removal of any one or more thereof when 20 desired, without disturbing or tangling the threads unremoved.

A plurality of hinged, relatively spaced flaps or leaves are utilized to hold the thread in the manner stated, it being understood 25 that the threads above held are to be properly and previously folded or arranged.

In describing my invention in detail reference will be had to the accompanying drawings wherein like characters denote like 30 or corresponding parts throughout the several views, and in which:—

Figure 1 is an elevation of my improved thread holder illustrating the manner in which the threads are folded or prearranged.

35 Fig. 2 is an end view of the holder, folded.

Fig. 3 is an enlarged section on the line 3—3 of Fig. 1, and

Fig. 4 is a section on the line 4—4 of Fig. 1.

40 Before proceeding with the description of the drawings I desire to call particular attention to the fact that while I have evolved my invention with reference to its use as a device for displaying and holding either 45 floss or silk threads, the same, if desired, may be used to display and hold twine, cord, cotton thread and such like materials.

Referring now to the drawings by numerals, 1 designates as an entirety my improved holder, the said holder in its preferred embodiment comprising duplicate 50 relatively movable or foldable sections 2 and 3. Said sections 2 and 3 being in duplicate a description of but one section will 55 ensue.

While the holder or display case is prefer-

ably of leather, canvas or duck, the material used, from a patentable standpoint is immaterial. The material used however must be durable, flexible and strong since this material designated 4 in the drawings serves as the outside covering for the holder or case. Two or more inflexible strips of material such as cardboard 5 are fastened to the covering material 4, each strip creating a holder 60 section (two are illustrated, although more may be provided if desired). As before stated, the sections illustrated are designated 2 and 3.

Where but two sections are used, each 70 section is braced longitudinally by means of reinforcing strips 6 and 7, the former, 6, extending adjacent the outside marginal edge of the section with which it is associated, and the latter, the strip 7 extending adjacent 75 the inside marginal edge of said section, the strips 7 (there being two where but two sections are provided) being suitably spaced as illustrated in Figs. 1 and 3, that the said sections 2 and 3 may be folded, one upon 80 the other, as illustrated in Fig. 2. A strip of material, the same as the covering material 4 is fastened to the strip 7, the said covering material engaging the said reinforcing strip 7 that said reinforcing strip 85 with the covering material 4 at the particular point where the sections 2 and 3 are connected, may reinforce the holder at the point where it "breaks" when folded. The outside marginal strips 6 are covered by the 90 material 4, said material overlapping said strips as illustrated in Fig. 3.

Each section of the holder is provided with a plurality of flaps or leaves (preferably three) designated respectively 8, 9 and 95 10, the several leaves being uniformly spaced and hingedly connected by the strip 7' to the inside marginal strips 7. Each flap or leaf is equipped with a button clasp that it may be releasably fastened at its free end 100 against movement with respect to its associate section or support. Each of the several leaves is further equipped with a finger engaging loop 13 whereby said flap or leaf may be released from its fastening engagement with its associated section by exerting 105 a pull thereon.

In assembling the floss or thread, it is to be understood that each thread is of a predetermined length. The thread is folded 110 upon itself as indicated in Fig. 1 and, when fastened against the holder by the engage-

ment of flaps 8 and 10 therewith, that portion of the thread extending above the uppermost flap being then folded over and upon the outside of said flap to be held in place by the intermediate flap 9. The manner in which the flap is held when completely folded is also illustrated in Fig. 1. In folding, it will be noted that the terminals of the thread are engaged by the flap 10. When folded properly, any one of the many threads displayed or held by the holder may be singly removed by simply exerting a pull thereon, it being unnecessary to detach or release any one of the flaps 15 which afford the holding means. The looped end of the thread should be grasped and the thread removed by exerting on said looped end the pull necessary to extraction. By the particular arrangement described, 20 tangling is obviated.

In transporting the display case from place to place it is to be understood that the sections 2 and 3 are to be folded one upon the other so that the threads thus incased 25 may be protected.

In reduction to practice, I have found that the form of my invention illustrated in the drawings and referred to in the above description, as the preferred embodiment, 30 is the most efficient and practical; yet realizing that the conditions concurrent with the adoption of my device will necessarily vary, I desire to emphasize the fact that various minor changes in details of construction, proportion and arrangement of 35

parts may be resorted to, when required, without sacrificing any of the advantages of my invention, as defined in the appended claims.

Having thus fully described my invention, 40 what I claim as new and desire to secure by Letters Patent is:—

A thread holder comprising a pair of leaves hingedly connected together for relative movement, a longitudinally extending 45 reinforcing strip secured to the inner face of each leaf adjacent the point of connection thereof, transversely extending extensions on said strips, a strip of equal thickness secured to the inner face of each leaf 50 adjacent the outer edges thereof, flaps secured to the ends of the transverse extensions of the inner strip, of each leaf, an intermediate flap secured to the intermediate extension of the inner strip, the thickness 55 of the flap corresponding to the thickness of the strips, and a separate fastening means for each flap to secure the same to their respective leaves, whereby skeins of yarn may be held therein with a portion of the skein 60 held beneath the end and intermediate flaps, and a portion thereof held above the end flaps and beneath the intermediate flap.

In testimony whereof I affix my signature in presence of two witnesses.

EDWARD A. TURNER.
